COSMETIC CONTAINER

Stanley Sapery, Brooklyn, N. Y., assignor to Victor Metal Products Corporation, Brooklyn, N. Y.

Application December 20, 1939, Serial No. 310,238

5 Claims. (Cl. 132—79)

This invention relates to ladies' cosmetic containers and more particularly to a cosmetic container adapted to hold both perfume and lipstick.

Prior to the instant invention it has been customary for ladies to carry in their purses or handbags various cosmetic containers, including a lipstick container and a perfume bottle. As it is well known that space in a lady's purse or handbag is at a premium, the problem involved 5 in the saving of space in ladies' purses and handbags for other articles than cosmetic containers is a very important one.

In addition to the above and also prior to the instant invention, it has been an actual fact 15 that there is a problem involved in the finding of particular items in ladies' purses and handbags by their owners and the particular article sought at any particular moment seems to be the last one to be found, much to the chagrin of 20 the owner of the purse or handbag.

It is an object of the instant invention to economize on space in ladies' purses and handbags and also to reduce the time involved in finding a particular article in ladies' purses and 25 handbags by providing a perfume flacon having a cap adapted to hold a lipstick and a cover therefor. As both the lipstick and the perfume make up a single article, whether the owner of the purse or handbag is looking for the perfume 30 or the lipstick, her chances are twice as great of finding the article sought in a predetermined time, or there is an even chance that she will find the article sought in half the time.

It is a further object of the instant invention 35 to provide a novel and attractive plural compartment receptacle which may be readily fabricated of inexpensive materials and in which the association of parts is such that they may be readily assembled and disassembled at the convenience of the user.

Other objects and the nature and advantages 40 of the invention will be apparent from the following description taken in conjunction with the accompanying drawing, wherein:

Fig. 1 is an enlarged view in elevation of a plural compartment receptacle in accordance 45 with the invention;

Fig. 2 is a longitudinal sectional view taken at right angles to the view shown at Fig. 1 and with the cord and tassel removed; and

Fig. 3 is a top plan view of the plural compartment receptacle with the cord and tassel removed.

Referring to the drawing, the plural compartment receptacle 10 includes a perfume flacon 11

which may be molded of glass and of polygonal horizontal section. The upper portion of the flacon 11 has a neck 12 which is formed with an annular ridge 13 and screw threads 14. At the junction of the lower portion of the neck 12 with the body of the flacon 11 there is a shoulder 15 on which the lower edge 16 of the cap 17 rests when in fully closed position.

The cap 17 is formed with screw threads 18, which cooperate with the screw threads 14 formed on the neck 12 of the flacon 11. The cap 17 is formed at its lower end with a skirt 19, the lower portion 16 of which cooperates with the shoulder 15. The skirt 19 completely covers and protects the annular ring 13 and provides for a 15 relatively smooth transition between the cap 17 and the sides of the flacon 11. Formed in the inner upper part of the cap 17 is a recess 20, which may be slightly undercut in order that it may better hold the gasket 21, which cooperates with 20 the uppermost portion 22 of the neck 12 of the flacon 11, whereby when the flacon 11 is screwed into the cap 17, there will be no danger of escape of the perfume within the flacon 11. Screwing in or out of the flacon 11 is facilitated by the 25 polygonal horizontal section thereof which may be readily grasped by the user and turned. The upper portion of the cap 17 is formed with a tubular projection 23 of an outer diameter which is less than the diameter of the cap 17.

The tubular projection 23 is adapted to receive 30 and hold a lipstick 24 within its interior and to receive and hold a closed end tubular member 25 on its exterior. The difference in diameter between that of the exterior of the tubular projection 23 and that of the exterior of the cap 17 corresponds to the space occupied by that portion of the closure member 25 which frictionally engages the exterior of the tubular projecting portion 23, whereby there is a smooth transition 35 between the cap 17 and the closure element 25 and the net result will be a relatively small plural compartment receptacle adapted to hold perfume and lipstick without danger of spilling and with the occupation of but a minimum of 40 space.

The closure element 25 includes a rounded 45 closed end 26 and a tapered fin 27, pierced at 28 to receive a cord 29, to which may be attached a tassel 30.

In the manufacture of the flacon 11, the reduced neck 12 is formed with the annular ring 13. The free end of the neck 12 is then formed with screw threads 14, while it is held by the annular ring 13. In order to protect the annular ring 55

13 and also to provide a smooth transition between the cap 17 and the flacon 11, in order to prevent the catching of dust and small particles in any exposed groove, the cap 17 is formed 5 with the skirt 18, which protects and covers the annular ring 13 and cooperates with the shoulder 15 of the flacon 11.

The association of the flacon 11 with the cap 17 depends upon the screw threads 14 and 18 10 and the gasket 21. The association of the closure element 25 with the cap 17 depends upon a friction fit between the interior of the lower portion of the closure element 25 and the exterior of the tubular projecting portion 23. The diameters 15 of the respective parts mentioned are so related that there will be a smooth transition between the exterior of the closure element 25 and the cap 17, in order to prevent the accumulation of dust and other small particles at the joints. Both 20 the fin 27 and the polygonal transverse section of the flacon 11 facilitate the assembly and disassembly of the parts to conveniently provide access to and seal, as desired, the cosmetics within the compartments of the plural compartment container. 25

The flacon 11 may be made of glass and the cap 17 and closure element 25 of a synthetic plastic which may be a phenol formaldehyde resin. The gasket 20 may be of paper, cork, 30 rubber, or other resilient material.

Thus it will be understood that a novel and useful plural compartment receptacle has been provided which solves problems of space, convenience, and sanitation for ladies, and at the same time reduces the expense to the manufacturer and consumer for articles of this nature. 35

It will be obvious to those skilled in the art that various changes may be made in this devise without departing from the spirit of the invention and 40 therefore the invention is not limited to what is shown in the drawing and described in the specification but only as indicated in the appended claims.

What is claimed is:

45 1. A combined lipstick and perfume container comprising a flacon having a body portion, a shoulder portion, and a reduced neck portion formed with an annular holding ring and screw threads, a cap for said flacon being formed in its upper inner portion with a recessed undercut depression, a gasket in said depression, said cap being formed with screw threads in its upper inner side walls which screw threads cooperate with the screw threads on the neck of the flacon, 50 said cap being provided with an extending skirt completely covering the annular holding ring and contacting the shoulder portion when the said cap and the flacon are associated with each other in closed position, said cap being formed with an extending tubular portion at its upper end, the outside diameter of which being less than the diameter of said cap, said tubular extending portion adapted to hold a lipstick, a closure ele- 55

ment including a tubular body portion closed at one end frictionally engaging the exterior of the tubular portion extending from said cap, the exterior diameter of said closure element and said cap being substantially the same. 5

2. A combined lipstick and perfume container comprising a flacon having a body portion and a reduced neck portion, a shoulder at the junction of said body portion and said neck portion, a cover for said flacon, said cover comprising a 10 partition contacting the top of said flacon and two tubular extending portions, said tubular extending portions being of different exterior diameter, one of said tubular extending portions corresponding to the diameter of said flacon, a 15 closure element associated with the other of said tubular extending portions, said last mentioned tubular extending portion adapted to hold a lipstick.

3. A combined lipstick and perfume container 20 comprising an elongated flacon of polygonal section, said flacon at its top portion having a reduced neck and a shoulder where said reduced neck portion joins the remainder of said flacon, a cover for said flacon having a portion in screw 25 thread relation with the exterior of said neck portion and cooperating with said shoulder, said cover also including a partition cooperating in sealed relation with the top of said flacon, a housing for said lipstick, said cover also being formed 30 with a combined means of holding a lipstick and for frictionally engaging the housing.

4. A plural compartment container comprising a flacon having walls forming an open mouth, a cover for said flacon comprising side walls and 35 a partition adapted to contact the upper part of said flacon and close its mouth, said cover including a cup-like depression on the opposite side of said partition for holding a lipstick, a closure cooperating with said cover about the exterior of 40 said cup-like depression to house said lipstick.

5. A plural compartment container comprising an elongated flacon having a relatively narrow neck portion adjacent its open top and a wider body portion, a cover for said flacon including a partition and side walls, said partition cooperating with the mouth of the flacon to close same and said side walls enveloping the exterior of the said neck portion of the flacon and being of a thickness corresponding to the difference in 50 width between the neck portion and the body portion of the flacon, said cover further including projecting walls on the other side of said partition to form a cup-like depression adapted to hold a lipstick, the exterior dimension of said projecting walls being less than the width of the body portion of said flacon, a second cover adapted to cooperate with the said projecting walls to form a housing for the said lipstick, said second cover being of a width corresponding to the width of the 55 body portion of the flacon. 60
